UNITED STATES PATENT OFFICE.

JOSEPH HALSTEAD, OF BURNLEY, ENGLAND.

CORSET.

SPECIFICATION forming part of Letters Patent No. 642,904, dated February 6, 1900.

Application filed March 29, 1899. Serial No. 710,912. (No model.)

To all whom it may concern:

Be it known that I, JOSEPH HALSTEAD, a subject of the Queen of Great Britain, and a resident of 13 Ormerod road, Burnley, in the county of Lancaster, England, have invented a new and useful Improvement in Corsets or Stays, of which the following description, together with the appended sheets of drawings, is a specification.

10 My invention relates to the construction of corsets or stays whereby they may be readily altered to suit several sizes of wearers with an equal degree of exactness and to be durable and efficient when in use in any of their 15 positions.

To attain the object of my present invention, I construct the corsets so that one part may be folded over another or so that they may be opened out to their fullest extremities and when in any of such relative positions afford the same facilities for their being laced together as are afforded by corsets as usually constructed; and in carrying my 20 invention into effect I follow the method of construction hereinafter described and as 25 illustrated by the accompanying sheets of drawings, in which—

Figure 1 is an elevation showing the corset with the parts folded and laced together 30 to form the least size. Figs. 2 and 3 are similar views to Fig. 1, but show the corsets with the parts arranged and laced together to form, respectively, one and two sizes larger corsets than those shown by Fig. 1. Fig. 4 is a trans- 35 verse view, on an enlarged scale, of the folding parts of the corset as in their position shown by Fig. 1. Fig. 5 is a similar view to Fig. 1, but illustrates the parts as when in the position shown by Fig. 3. Figs. 6 and 7 40 are similar views to Figs. 2 and 3, respectively, but illustrate a modification herein- 45 after explained. Figs. 8 and 9 are similar sectional views of Figs. 6 and 7 that Figs. 4 and 5 are of Figs. 1 and 3.

Similar letters indicate similar parts throughout the several views.

In carrying my invention into effect I form two series of eyelet-holes $a\ b$ and $a'\ b'$ in each of the edges c and d of the corsets, to be joined 50 together by a cord or lace f , series b and b' being nearer the outer edges than are the series a and a' ; but in each case the series a or a' is

in such relative proximity with its respective series b or b' that when the part g or g' is folded over (see Fig. 4) the one series will in each 55 case exactly overlie the other in order that the lace f may pass through all the several eyelet-holes, as shown by Fig. 1, while the folded edges at h will form the outer edges of the 60 corsets and the least size is produced.

By turning out or opening the part g or g' (the part g' being shown by Fig. 2) so that the lace f will only pass through one series of holes, as at z' , Fig. 2, but through the two series $a\ b$, the next larger size of corset 65 is produced, while by opening both parts out, as shown by Figs. 3 and 5, another larger size of corset is produced.

As a modification in the construction above described I employ a separate piece k , (shown by Figs. 6 to 9, inclusive,) which may be thus made to go with the ordinary kind of corset as at present constructed, with its two usual series of lace-holes $m\ m'$. In this case the several series of eyelet-holes $a\ b$ and $a'\ b'$ are 70 made in their respective positions in the piece k , as shown, so that when one part of the said piece k is folded over the other (see Figs. 6 and 8) they (said respective series of holes $a\ b$ and $a'\ b'$) will coincide with each other. 75

In order that the several parts may be folded as above described, I reduce the thickness of the fabric forming the corset at the part, as at p , where the fold is produced, and to make the corset durable and efficient I secure the 80 usual strengthening-strips s of metal, whalebone, or the like in such positions relatively with the series of holes that one of such strips s intervenes at all times between the series of holes and each outer edge of the 85 parts brought together by the lacing. 90

Although I have only shown my invention as applied to a corset or stay laced at the back, I wish it to be understood that I am well aware that it can be applied with equal 95 advantage to corsets or stays having their lacing-eyelets arranged in any other position, such as at the front, sides, or other parts thereof.

Such being the nature and object of my invention, what I claim is— 100

1. A corset comprising two independent sections having foldable lacing edges each fold having lacing-eyelets arranged in series,

said series being adapted to coöperate interchangeably with each other, whereby the size of the corset may be uniformly adjusted from top to bottom by the foldable edges, and variably adjusted by the lacing.

5 2. In an article of wearing-apparel, the combination of two independent and separate meeting edges each having a foldable part each part having eyelets arranged in series,

and a lace adapted to be passed through said series of eyelets interchangeably, the said meeting edges being connected by said lace.

In testimony whereof I have affixed my signature in presence of two witnesses.

JOSEPH HALSTEAD.
